UNITED STATES PATENT OFFICE.

WILLIAM C. PRICE, OF BEATTYVILLE, KENTUCKY.

LOCK-NUT.

1,228,130.

Specification of Letters Patent.

Patented May 29, 1917.

Application filed February 24, 1917. Serial No. 150,757.

To all whom it may concern:

Be it known that I, WILLIAM C. PRICE, a citizen of the United States, residing at Beattyville, in the county of Lee and State 5 of Kentucky, have invented a new and useful Lock-Nut, of which the following is a specification.

This invention relates to nut locks, one of its objects being to provide a simple, compact and efficient lock which can be used in connection with rail joints, sucker rods, and in fact wherever it is desirable to hold against accidental independent rotation two engaging threaded elements.

15 A further object is to provide a nut lock which will not interfere with the unscrewing of the connected parts provided they are subjected to excessive force.

With the foregoing and other objects in view which will appear as the description proceeds, the invention resides in the combination and arrangement of parts and in the details of construction hereinafter described and claimed, it being understood that 20 changes in the precise embodiment of the invention herein disclosed, can be made within the scope of what is claimed, without departing from the spirit of the invention.

In the accompanying drawings the preferred forms of the invention have been shown.

In said drawings:—

Figure 1 is a vertical transverse section through a rail joint having the present improvements combined therewith.

Fig. 2 is a section on line 2—2 Fig. 1.

Fig. 3 is a section on line 3—3 Fig. 1.

Fig. 4 is an elevation of the nut and showing the locking spring out of normal position.

Fig. 5 is a view partly in section and partly in elevation of portions of a sucker rod having the present improvements combined therewith, the several parts being disconnected.

Fig. 6 is an enlarged view through the structure shown in Fig. 5, said parts being shown fastened together.

Fig. 7 is a section on line 7—7 Fig. 6.

50 Fig. 8 is a section through a modified form of lock.

Referring to the figures by characters of reference 1 designates a railway rail interposed between fish plates 2 through which 55 extends an ordinary bolt 3. One of the fish plates has a counter bore 4 the wall of

which is waved or corrugated as indicated at 5 in Fig. 3. Seated in this counter bore is a split ring 5 preferably formed of spring metal and which is corrugated or waved from one end to the other so that when it is in its normal position it will fit snugly against the corrugated wall of the counter bore as shown in Fig. 3. The nut 6 has a counter bore 7 the wall of which is corrugated or 60 waved as indicated at 8 in Fig. 2, these corrugations coinciding with those in the counter bore 4. The width of the locking strip or ring 5 is such that when the nut 6 is in contact with the fish plate 2 said locking ring will project into both counter bores 4 and 7. Obviously by rotating the nut 6 by applying excessive power thereto, the corrugations in the nut will slip over the corrugations of the locking ring 5, thus contracting the ring and causing it to rotate within the counter bore 4. After the nut has been tightened and the corrugations in the two counter bores brought into register the locking ring will expand so as to fit 70 snugly against the corrugations of the two counter bores, thereby holding the nut against unscrewing unless subjected to excessive power.

While the improvements are especially 85 useful in connection with rail joints, they can also be used under other conditions. For example, where the two sections 9 and 10 of a sucker rod are to be fastened together, a counter bore 11 can be provided 90 at the outer end of the threaded bore 12 in section 9 while a recess 13 can be formed in the section 10 around the threaded stud 14 thereon. The walls of the counter bore 11 and recess 13 are corrugated so as to be 95 of the same configuration and a split locking ring 15 which is corrugated and which is similar to the ring 5 is adapted to rest within the counter bore 11 and the recess 13. Thus when the stud 14 is screwed into the bore 12 the corrugations in the counter bore 11 and recess 13 will operate to contract the ring and when the two sections of the sucker rod have been brought together with the corrugations matching, 100 then the ring 15 will fit snugly against the corrugations and hold the sections of the sucker rod against separation unless subjected to excessive power.

Another form of the invention has been 105 illustrated in Fig. 8 and is designed to be used where the nut co-operates with a wooden

structure. In this modified form, the wooden structure has been indicated generally at 16 and is provided at diametrically opposed points with recesses 17 for the reception of lugs 18 extending from one face of a metal washer 19. This washer has its inner wall corrugated to agree with the corrugated wall 21 of a counter bore 22 formed in a nut 23.

10 A corrugated split ring 24 of spring material is adapted to fit snugly in the recess 22 and within the washer 19, one edge of this ring bearing against the wooden structure 16. Thus it will be seen that when the 15 nut is screwed onto the bolt 25 the corrugated ring 24 will be contracted within the washer 19 and the counter bore 22 until the nut is brought tightly against the washer and the corrugations in the counter bore 20 and in the washer come into register. Ring 24 will then fit snugly against both sets of corrugations and hold the nut against rotation relative to the washer unless subjected to excessive power. Obviously the lugs 18 25 will prevent the washer from rotating about the bolt and relative to the structure 16.

What is claimed is:—

1. The combination with a structure having a recess provided with a corrugated

wall, and a threaded member extending 30 through the center of the recess, of a member screwed onto the threaded member and having a recess provided with a corrugated wall, the two corrugated walls being spaced from the threaded member, and a corrugated locking ring projecting into both recesses and adapted to fit snugly against the corrugated walls, said ring being contractible during the relative rotation of the two members.

2. The combination with a member having an inner corrugated wall and a threaded element extending through said member, of a second member screwed upon said element and having a recess provided with a corrugated wall coinciding with the wall in the first named member, and a split spring ring projecting into both members and spaced from the threaded element, said ring being corrugated to conform with the corrugations in the members.

In testimony that I claim the foregoing as my own, I have hereto affixed my signature in the presence of two witnesses.

WILLIAM C. PRICE.
